GEORGE H. BUCKLEY, OF INDIANAPOLIS, INDIANA.

ELECTRIC PLUG.

1,194,137.

Specification of Letters Patent.

Patented Aug. 8, 1916.

Application filed December 26, 1914. Serial No. 879,132.

To all whom it may concern:

Be it known that I, GEORGE H. BUCKLEY, a citizen of the United States, and a resident of Indianapolis, county of Marion, and State of Indiana, have invented a certain new and useful Electric Plug; and I do hereby declare that the following is a full, clear, and exact description thereof, reference being had to the accompanying drawings, in which like letters refer to like parts.

The object of this invention is the improvement of electrical plugs for making connections and disconnections, in residences and elsewhere. Heretofore, such plugs have been soldered and made of one piece and adapted to screw into the sockets and it takes time to screw the plug fully into the socket and disconnect the same and it requires a turning movement of the plug which is often interfered with by the electric lines or cords and often injures the lines and cords.

The chief feature of this invention consists in making such a plug so that it can be slipped longitudinally into a threaded socket and so that it may be put in place instantly and instantly removed without subjecting the cord or line to any twisting movement.

The full nature of the invention will be understood from the accompanying drawings and the following description and claims:

In the drawings, Figure 1 is a longitudinal central section of the plug in place in a socket and the socket being partially in section and partially in elevation. Fig. 2 is a plan view of the device showing the plug in position for removal. Fig. 3 is a section on the line 3—3 of Fig. 1. Fig. 4 is a section on the line 4—4 of Fig. 1.

There is shown herein a lamp socket 10 of ordinary type having an internally threaded sleeve 11 which is made of metal and constitutes one terminal and there is another central terminal 12.

The plug consists of two members, one member 13 which may be called a stationary member and another member 14 which is a slidable or movable member, being slidable upon and in connection with said member 13, as shown in Figs. 1 and 3. The handle or member 13 has a central longitudinal groove 15, preferably circular in which a cable containing the lines 17 and 18 are

located. The line 17 is connected with a binding post 19 in the end 20 of the member 13, which end is formed of hard rubber or other insulating material. The binding post 19 is secured to a terminal 21 adapted to engage the terminal 12 in the socket when the plug is inserted. The other line 18 is connected with a binding post 22 in the hard rubber portion 20 of the plug and is connected with a metal threaded plate or cover 23 which surrounds the outer periphery of the hard rubber part 20, as seen in Fig. 4. As shown in Fig. 3, the hard rubber end of the stationary member 13 is slightly more than semi-circular and, therefore, the threaded plate 23 is slightly more than semi-circular and its threads correspond with the threads of the sleeve 11 in the socket. At the outer end of member 13 the usual slip connection 25 is provided.

The member 14 is less than semi-circular and has a pair of arms 26 extending into the recesses 15 of the member 13. These arms, as shown in Fig. 3, are curved in opposite directions so as to be slidable in said recesses. Therefore, the member 14 is slidable with reference to the member 13. The member 14 has a tapering hard rubber end member 28 adapted to wedge into the socket between the inner wall of the socket or threaded sleeve 11 and the hard rubber portion 20 of the other member of the plug and hold the latter in connection with the threaded sleeve 11, as shown in Fig. 1. This will make as permanent connection between the plug and socket as is provided with the ordinary screw plug.

To remove the plug from the socket, the member 14 is slipped from the position with reference to the member 13, shown in Fig. 1, to that shown in Fig. 2, so that its inner end is outside or disengages the socket. Then the inner end of the member 13 can be moved laterally enough to disengage the threads of the plates 11 and 23 and it can be then withdrawn from the socket. In order to enable this to be done, the inner end of the member 13 should not be much more than a semi-circle. This enables the plug to be withdrawn from the socket without turning it. Likewise the plug can be inserted in the socket without turning it. This is done by holding the two members 13 and 14 in the position shown in Fig. 2, and inserting the end of member 13 into the

socket so that the threads of the plates 11 and 23 will engage each other. Then the inner end of the plug 13 is shoved up in the socket so as to wedge the plug in the 5 socket. The device is easily operated by one hand, the hand holding the member 13 stationary while with the thumb the member 13 is moved one way or the other to engage or disengage the socket, as desired.

10 The invention is shown herein long enough to be manipulated with one's hand, but it is not limited to a plug of any particular length or size.

The invention claimed is:

15 1. An electric plug adapted to engage a socket, said plug having a plurality of members, one of said members having an inner longitudinal groove, and guiding and holding means extending from the other 20 member into said groove, whereby the two members may be longitudinally moved independently of each other, the end of the grooved member being formed to engage the inner wall of the socket and the end of the 25 other member being smooth and wedge shape

for wedging between the end of said grooved member and the wall of the socket.

2. An electric plug adapted to engage a socket, said plug having a plurality of members, one of said members having an inner 30 longitudinal groove, guiding and holding means extending from the other member into said groove, whereby the two members may be longitudinally moved independently of each other, the end of the grooved member 35 being formed to engage the inner wall of the socket and the end of the other member being smooth and wedge shape for wedging between the end of said grooved member and the wall of the socket, and electrical 40 conductors located in the groove of said grooved member.

In witness whereof, I have hereunto affixed my signature in the presence of the witnesses herein named.

GEORGE H. BUCKLEY.
